UNITED STATES PATENT OFFICE.

THOMAS R. COOK, OF PITTSBURGH, PENNSYLVANIA.

DESIGN FOR A CONNECTING-STRAP FOR SECONDARY BATTERIES.

56,654.

Specification for Design. Patented Nov. 23, 1920.

Application filed August 10, 1920. Serial No. 402,701. Term of patent 14 years.

To all whom it may concern:

Be it known that I, THOMAS R. COOK, a citizen of the United States, residing at Pittsburgh, in the county of Allegheny and State of Pennsylvania, have invented a new, original, and ornamental Design for a Connecting-Strap for Secondary Batteries, of which the following is a specification, reference being had to the accompanying drawing, forming part thereof.

In the drawing:

Figure 1 is a top plan view of the strap;

Fig. 2 is a side view thereof, and Fig. 3 is an end view of the strap.

I claim:

The ornamental design for a connecting strap for secondary batteries, as shown.

THOMAS R. COOK.
